UNITED STATES PATENT OFFICE.

FRANK BRONORI, OF BENNINGTON, VERMONT.

COIN-ACTUATED MECHANISM.

SPECIFICATION forming part of Letters Patent No. 683,678, dated October 1, 1901.

Application filed November 1, 1900. Serial No. 35,150. (No model.)

To all whom it may concern:

Be it known that I, FRANK BRONORI, a citizen of the United States, residing at Bennington, in the county of Bennington and State of Vermont, have invented certain new and useful Improvements in Coin-Actuated Mechanism; and I do hereby declare the following to be a full, clear, and exact description of the invention, such as will enable others skilled in the art to which it appertains to make and use the same.

This invention relates to the class of apparatus commonly designated as "slot-machines," and embodying a number of different mechanisms connected with a prime motor actuated by the deposition of a coin of determinate value into a slot.

The primary object of this invention is to simplify the construction and materially reduce the cost of manufacture and maintenance and enable the working parts to be compactly arranged. These ends are attained in a great measure by the direct mounting of the parts—such as the vending mechanism, the music-cylinder, and the view belt or support—upon the arbors or shafts of the gear elements of the train of gearing.

The invention also aims to prevent operating the machine by means other than the predetermined coin and to guard against the not uncommon practice of dropping a dummy, slug, or kindred article and demanding of the proprietor or person exhibiting the machine an amount equal to the value of the coin required to actuate the machine on the plea that the machine failed to work.

Other objects and advantages will become apparent as the invention is comprehended, and for a full description thereof and also to acquire a knowledge of the details of construction of the means for effecting the result reference is to be had to the following description and drawings hereto attached.

While the essential and characteristic features of the invention are necessarily susceptible of modification, still the preferred embodiment of the invention is illustrated in the accompanying drawings, in which—

Figure 1 is a perspective view of the vitals of a slot-machine embodying the invention, the dotted lines showing the outline of the

cabinet. Fig. 2 is a detail view of the coin-controlled mechanism and the means actuated by the coin to permit the starting of the operating mechanism. Fig. 3 is a view of the operating parts shown in Fig. 2, the coin-chute and cabinet being removed. Fig. 4 is a detail view of the stereoscope and upper portion of the view or picture mechanism, showing the illuminator, the electric circuit, and the circuit-closing means. Fig. 5 is a detail perspective view of the upper portion of the coin-chute.

Corresponding and like parts are referred to in the following description and indicated in all the views of the drawings by the same reference characters.

The power-actuated shaft 1 is provided with a gear-wheel 2 and a vending mechanism 3 of any desired type, and this shaft is the primary means from which motion is imparted to the train of gearing for actuating the operating parts of the machine. Any motive power may be applied to the shaft 1 to drive the same, and for convenience a weight 2 is shown, and a cord 3, attached to the weight 2, is adapted to wind around the said shaft, the winding being effected by means of a crank or key in the well-known manner. A pinion or comparatively small gear-wheel 4 is in mesh with the gear-wheel 2 and is secured to a shaft 5, paralleling the shaft 1, and upon which the pin-cylinder 6 of a music mechanism is secured, so as to rotate therewith, the pins of the cylinder coöperating with the teeth of a cone 7 in the usual way. A gear-wheel 8 is secured to the shaft 5, so as to turn therewith, and is in meshing relation with a gear-wheel 9, of smaller diameter, secured to an end portion of a shaft 10, parallel with the shafts 1 and 5. A pin 11 projects laterally from a side of the gear-wheel 9 and coöperates with a spur-wheel 12, secured to a journal of the rotary support 13 of the view or picture mechanism. A gear-wheel 14 is secured to the shaft 10 and is in mesh with a pinion 15, secured to the fan-shaft 16 in parallelism with the shafts 1, 5, and 10. The train of gearing has its speed regulated by means of the fan 17 in the well-known manner, and the parts to be driven are mounted directly upon the shafts or axes of the vari-

ous gear elements. Hence compactness is secured and the machine can be run with the expenditure of a minimum amount of force.

The vending mechanism 3 consists of a drum 5 surrounded by compartments which receive the packages or articles to be delivered, a chute 18 directing the packages into an outlet 19, formed in a side of the cabinet, where they are readily accessible to the person playing the machine. When the last package or article has been delivered, a visual and an audible signal are operated to warn the player that the machine is empty. The audible signal consists of a gong 20 and a hammer 21, mounted upon a lever 22, having one end projected in the path of a pin or stop 23, provided at one side of a gear-wheel 2. The visual signal consists of a placard 24, attached to a stem 25, connected with the lever 22. When the vending cylinder or drum is charged with packages or articles to be delivered, the placard 24 is withdrawn within the cabinet, so as not to be observed, and as soon as the last package or article is delivered the pin 23 strikes the lever 22 and simultaneously sounds the gong and throws the placard 24 into position to be readily seen by the player, so as to apprise the person of the fact that the machine is empty.

30 The motive power is held in restraint by a detent mechanism which is released upon the deposition of a coin of determinate value into the coin-slot 26. This detent mechanism consists of a pin or stop 27, projected from a side 35 of the gear-wheel 8, and a spring-actuated pin, rod, or bolt 28, normally extending in the path thereof and mounted for reciprocating movement in a tube or guide 29. The spring 30, by means of which the pin or rod 28 is held 40 projected, is located within the tube or guide 29 and is exceedingly light and of sufficient strength to hold the pin projected in the path of the stop 27 and to be compressed by means of the coin striking the pan 31, attached to 45 the said rod 28. The coin-tube 32 is in communication at its upper end with the coin-slot 26, and its lower end terminates above the pan 31, so as to deliver the coin thereon. The upper portion of the coin-tube is deflected and 50 formed with an opening 33 to prevent a wire being directed through the tube to actuate the pan 31. The side of the tube adjacent the cabinet is cut away with the exception of narrow flanges 34, which engage with opposite edges of the coin and support the same during its passage to the pan 31. An article slightly smaller than the diameter of the prescribed coin will not follow the tube 32, but will drop directly therefrom and prevent operation of the machine.

To prevent imposition being practiced upon the proprietor or owner of the machine by parties dropping worthless articles into the machine and commanding the return of a 65 coin of the value required for operating the machine, the following instrumentalities are provided and consist of levers or arms 35 and

36, located the one above the other and pivoted between their ends, said arms having pans 37 and 38 at their ends adjacent to the 70 proximal side of the cabinet. Stops 39 and 40 limit the upward movement of the pans 37 and 38, and the arms 35 and 36 are weighted, so as normally to hold the pans 37 and 38 in the given position. An observation-opening 75 41 is provided in the side of the cabinet between the stops 39 and 40, and anything contained in the pan 38 is at all times visible through the opening 41, which is covered by glass or any transparent substance. Levers 80 42 and 43 are pivoted between their ends and are connected with the levers 35 and 36 by means of rods 44 and 45, so as to cause a simultaneous movement of the corresponding parts 42 and 36 and 43 and 35. Stops 46 and 85 47 project laterally from the gear-wheel 8 and are positioned so as to alternately actuate the levers 42 and 43. These stops or tappets 46 and 47 are located at different distances from the axis of the gear-wheel 8, according to the relative position of the ends of the levers 42 and 43, contiguous to said gear-wheel. When the machine is at rest, the coin last operating the machine is located in the pan 38 in position to be easily seen 90 through the observation-opening 41, and upon the deposition of another coin into the slot 26 the gear-wheel 8 is released from the detent or rod 28 by means of the pan 31 being depressed. As the gear-wheel 8 revolves, 100 the stop 46 will strike the lever 42 and cause a depression of the outer end of the pan 38 and permit the discharge of the coin into the coin-receptacle 48, and just prior to the stopping of the machine the trip 47 will actuate 105 the lever 43 and depress the pan 37 and permit the coin received thereon from the pan 31 to drop onto the pan 38, where it will be held until the machine is again operated in the manner stated. Should the machine fail 110 to operate from any cause, the article drops through the slot 26 and will be retained upon the pan 37, and should the same be a dummy, 115 slug, or other valueless article the same will be apparent to the proprietor or person exhibiting the machine upon inspection, thereby preventing the perpetration of fraud by a dishonest person. On the other hand, should the object received upon the pan 37 be a coin 120 it will be evident that the claim of the party 125 playing the machine in the event of the latter failing to operate is just and that a refund of the coin should be made, thereby preventing loss to the player in the event of the machine failing to respond when a coin 125 of determinate value has been properly deposited.

The view or picture mechanism consists of an endless belt 49, composed, preferably, of plates bearing the desired pictures to be exhibited, said plates being transparent. This picture-belt is supported at its upper end upon a drum 13, of triangular form in cross-section, and at its lower end upon a corre-

sponding drum 50, the sides of the drums corresponding to the width or depth of the plates which rest thereagainst when in position to be viewed. The drums 13 and 50 are 5 preferably of skeleton form for the sake of lightness and also to permit the unobstructed passage of light-rays, by means of which the pictures are illuminated and displayed to the best possible advantage. The spur-wheel 12, 10 attached to a journal of the drum 13, consists of three spurs or arms corresponding to the three faces or sides of the drum, and these spurs are positioned so as to insure the proper location of the pictures with reference to the stereoscope when the machine is 15 in operation. The gear-wheel 9, carrying the pin 11, makes one complete revolution before the drum 13 is moved, so as to bring the next picture of the series in position for 20 observation, thereby giving ample time for a careful inspection of the picture before the same is changed. However, should the player desire to observe the picture for a greater length of time than is provided by the movement 25 of the train of gearing a retarding mechanism is provided and consists of a spring-actuated push-bar 51, located so that its inner end can be brought into engagement with a gear element of the train of gearing, 30 which in the present instance is the gear-wheel 9. Under normal conditions the inner end of the push-bar 51 is held away from the gear-wheel 9 by means of the spring 52, and when it is desired to check the movement of 35 the machine pressure is applied to the outer end of the push-bar 51 in such a manner as to bring the inner end into engagement with the gear-wheel 9. When the push-bar is released, the operating mechanism will resume 40 movement until the stop 27 comes into engagement with the rod 28, when the machine will come to rest until again actuated by a coin of required value dropped into the slot 26. The stereoscope 53 may be of any pattern 45 and convenient location and is positioned so as to admit of the pictures being seen to the best possible advantage. An illuminator 54 is provided and consists of an electric incandescent light, and in order to light up the pictures the illuminator is located in an electric circuit of which the terminals are located at 55 and 56, the latter being fixed and the former movable and connected with a spring-actuated rod 57, having a button 58 at its outer end, positioned with reference to the stereoscope 53 so as to be pressed upon the forehead of the observer when viewing the pictures. Normally the electric circuit is open, and a slight pressure upon the button 60 58 completes the circuit and causes an illumination of the pictures, which are seen through the stereoscope in the ordinary way.

The goods to be vended are placed in the compartments of the drum of the vending mechanism 3, and the mechanism being properly adjusted a coin of predetermined value being dropped into the slot 26 passes through

the tube 32 and is received upon the pan 31 and passes therefrom onto the pan 37. When the coin is received upon the pan 31, the latter is depressed carrying the rod 28 with it and releasing the power-actuating shaft 1, which rotates slowly a distance corresponding to the width of a compartment, so as to bring a package or article to be delivered opposite the chute 18, through which it descends into position to be reached through the opening 19. Simultaneously with the operation of vending the music mechanism plays an air and the picture mechanism is 80 operated to exhibit views, thereby rendering the playing of the machine attractive and insuring a liberal patronage.

Having thus described the invention, what is claimed as new is—

1. In a machine of the character described, a train of gearing including a power-actuated shaft, a stop applied to a gear element of the train of gearing, a vertically-reciprocating spring-actuated rod projected in the path of the said stop, vertically-aligned guides for the end portions of the rod, a pan connected to the said rod intermediate the guide and movable therewith, and a coin-tube terminating above the pan so as to deliver the coin thereon and effect a release of the train of gearing, substantially as specified.

2. In a machine of the type described, a train of gearing including a power-actuated shaft, a coin-actuated detent mechanism to effect a starting of the machine upon the deposition of a coin of denominative value, coin-receptacles located the one above the other with an observation-opening opposite the space formed therebetween, and a trip mechanism for each coin-receptacle adapted to be alternately actuated, first to effect a discharge of the coin from the lowermost receptacle and then to cause the coin to drop from the upper receptacle upon the lower receptacle in position to be seen through the observation-opening, substantially as set forth.

3. In a machine of the character described, and in combination with the train of gearing including a power-actuated shaft, and a coin-controlled detent mechanism for effecting a release of the train of gearing, upper and lower coin-receptacles with an observation-opening therebetween, levers having independent connection with the respective coin-receptacles, and independent trips applied to an element of the train of gearing and disposed to actuate the lowermost receptacle and subsequent thereto the uppermost receptacle to permit the coin or object received thereon to drop to the lowermost receptacle opposite to the observation-opening, substantially as set forth.

4. In a machine of the character described, and in combination with a train of gearing including a power-actuated shaft, a stop applied to a gear element of the train of gearing, a spring-actuated rod normally extended in the path of the said stop and provided

with a pan, and a coin-tube arranged to deliver the coin upon the said pan, other pans located the one above the other with an observation-opening therebetween and adapted 5 to receive a coin from the first-mentioned coin-pan, levers connected with the last-mentioned pans, and trips applied to a gear element of the train of gearing and positioned to alternately actuate the said pans adjacent

to the observation-opening, substantially as ¹⁸ and for the purpose set forth.

In testimony whereof I affix my signature in presence of two witnesses.

FRANK BRONORI. [L. S.]
